CLAIM

The ornamental design for a candle set, as shown and described.

DESCRIPTION

FIG. 1 is a front perspective view of a candle set, showing my new design;

FIG. 2 is a rear perspective view thereof;

FIG. 3 is a front view thereof;

FIG. 4 is a rear view thereof; and,

FIG. 5 is a partial enlargement of FIG. 1.

The dash-dot broken lines represent the boundary of the enlarged view and form no part of the claimed design.
